UNITED STATES PATENT OFFICE

WILLIAM E. PAUL, OF SCHENECTADY, NEW YORK, ASSIGNOR TO GENERAL ELECTRIC COMPANY, A CORPORATION OF NEW YORK

ELECTRIC SWITCH

Application filed December 24, 1928. Serial No. 328,161.

My invention relates to electric switches and particularly to switches for interrupting modern alternating current commercial power circuit. Switches commonly used for controlling such circuits have their contacts arranged to separate beneath the surface of an insulating liquid such as oil contained usually in a closed vessel. It is well known to those skilled in the art that the amount of power that may be interrupted by such a switch is dependent to a large extent upon the amount of gas that is formed by the arc drawn between the contacts before it is finally extinguished. Any means therefore that will reduce the amount of gas formed in the switch or prevent it entirely is an important factor in effecting the interruption of the circuit.

This application is a continuation in part 20 of my application Serial Number 281,480, filed May 29, 1928, for electric switches, the disclosures of said prior application being embodied in this application together with additional matter.

25 One object of my invention is to provide an improved switch of this character which shall cause the contacts at the final break to separate only at or near the zero value of the current wave.

30 Another object of my invention is to provide improved means for causing any arc that may be drawn between the contacts of the final break to be transferred quickly from the contacts and the contacts to become insulated from each other by a layer of the insulating liquid.

35 Another object of my invention is the provision of a liquid break switch having main and arcing contacts and improved means for expelling laterally from the main contacts and the switch operating means any arc and gas formed at the arcing contacts.

40 A further object of my invention is the provision of a liquid break switch wherein the circuit is broken simultaneously at a plurality of points in series, the arcs at the several points being expelled laterally and the cooperating contacts immediately insulated from each other by insulating liquid.

45 50 My invention will be better understood

from the following description taken in connection with the accompanying drawings, and its scope will be pointed out in the appended claims.

Referring to the drawings, Fig. 1 is a view 55 partly in section and partly in elevation of a switch embodying my invention the parts being shown in closed circuit position; Fig. 2 is a sectional view of a portion of the same taken on the line 2—2; Fig. 3 is similar to 60 Fig. 1 except that it shows the switch in open circuit position; Fig. 4 is a cross sectional view of Fig. 3 showing the movable arcing contacts; Fig. 5 is a circuit diagram; and Fig. 6 illustrates a modification.

Through the top of the enclosing vessel 1 containing insulating liquid extend the insulating bushings 2 connected by braces 3 and surrounding the studs 4 in accordance with well known oil switch construction. At- 70 tached to the lower end of each bushing 2 is the housing 5 of insulating material shown as comprising integral top, bottom and inner side walls to which are attached by bolts 6 the side plates 7 of the outer side being left 75 open. The housing is also divided into a number of chambers, in the present case three, by the insulating partitions 8. The number of chambers provided depends upon the num-

ber of series breaks in the circuit which the 80 switch is desired to make and obviously the number may be varied to suit particular conditions. In the several chambers are similar blow-out coils, each comprising the coil 10 formed of several turns of flat conductor 85 around the core 11 and secured to the ends of each core are the plates 12 forming pole pieces, the shape of the plates being indicated by dotted lines in Fig. 1. One end of each coil connects with one of the fixed arcing contacts 13 arranged between the pole pieces 12.

The opposite end of one of the coils is connected directly by conductor 14 with the adjacent stud 4 while the opposite ends of the other two coils are connected together as shown in Fig. 2 and in the circuit diagram. The direction of current in the coils 10 is such that the magnetic flux between the pole pieces reacts with the arcs drawn from the contacts 31 to push them outwardly through the open 100

side of the housing. Thus the arcs in the two housings are expelled in opposite directions toward the adjacent tank walls and away from the main contacts and operating rod to be described later. Each chamber of the housings has the curved wall 15 and is shaped to form an arc chute, the coil being protected by the wall from the arc. On the outer face of this wall is the conducting arc runner 16 which connects at its lower end with the fixed contact 13. That part of the housing forming the lower wall of the arc chute has an opening to receive the movable arcing contact 17 and is provided with the barrier 18 below which is the conducting member 19. This member is slidably secured to the housing by the bolt 20 and is pressed against the side of the movable contact 17 by the spring 21. At the side of the fixed contact opposite the barrier 18 the housing is formed with the cavity 22, the purpose of which will be explained later.

The operating rod 25, the lower portion at least of which is of insulating material, has secured to it the main current carrying bridge 26 and the arcing contact bridge 27. The former bridge when the switch is closed contacts with the main fixed contacts 28 which are mounted on adjacent faces of the housings 30 and which by the conductors 29 connect with the studs 4. Bridge 27 comprises two transverse metal plates 30 fixed to the operating rod and having lateral projections bolted to the three pairs of insulating plates 31. At each end of each pair of plates there is secured the sleeve 32 in which slides the movable arcing contact 17. Movement of contact 17 in its sleeve is limited by the pin 33 fixed in the sleeve engaging the ends of the slot 34 in the contact. Coil spring 36 mounted within the contact between the upper end thereof and the pin holds the cooperating arcing contacts together during the initial opening movement of the switch. To bracket 37 secured to the bridge 31 is pivoted the arm 38 at the opposite end of which is the pawl 39 and on the side facing the pawl the contact 17 has a series of teeth or notches 40 forming a ratchet adapted to be engaged by the pawl. At its pivot end the arm is connected to the contact 17 by the flexible conductor 41 and at its opposite end it is connected by flexible conductor 42 to member 43 of the bridge. The two outer members 42 at each end of the bridge are electrically connected together by the strap 44 and the corresponding middle members 43 of the bridge are connected together by the strap 45. By the construction described it will be seen that arm 38 is a part of the circuit through the switch and forms one side of a loop of which the other side is the contact 17. By reason of the connection of the arm with the member 43 the arm also forms one side of a second loop which as shown is partly within the first mentioned

loop. In accordance with well known laws current traversing the switch produces in each loop a magnetic flux which tends to cause the loop to enlarge. The arm 38 forming as it does a corresponding side of both loops it tends to rotate in a direction to withdraw the pawl from the contact 17. This movement is opposed by the spring 47 whose tension is such that the pawl is caused to engage the ratchet on contact 17 when the instantaneous value of the alternating current is zero or is close to zero. A suitable stop 48 limits the movement of the arm 38 to a point at which the pawl just clears the ratchet teeth. Accordingly it will be noted that the pawl and ratchet form a disengageable clutch connection between the bridging member 27 and contact 17. When the switch is in closed circuit position illustrated by Fig. 1 the spring 36 is compressed thus holding contact 17 against contact 13. As the switch moves to open circuit position, main bridging member 26 separates from contact 28 transferring the load to contacts 13 and 17 which are held together by the force of spring 36. So long as the instantaneous value of the current wave is other than zero or near zero, arm 38 with pawl 39 will be held against stop 48 but as soon as the value of the current wave falls to zero or near zero the electromagnetic force on the arm 38 is overcome by the force of spring 47 and the pawl engages the ratchet. The bridging member 27 and associated parts have by this time gained greater speed and by the engagement of the pawl and ratchet quickly separate the arcing contacts 13 and 17. If this separation occurs exactly at the zero value of the current, no arc is drawn between these contacts. If however it does not occur exactly at zero but close to it, a small arc is drawn which is immediately expelled into the arc chute 11 by the blowout coil as indicated by the dot and dash lines in Fig. 3, the ends of the arc being transferred from the contacts 13 and 17 respectively to the runner 16 and the contact 19. This blowout action is very rapid so that the arc is broken while the instantaneous value of the current is still small. The arc in being transferred from contact 17 to contact 19 jumps the barrier 18 whence the arc current passes to or from contact 17 through the sliding connection between it and contact 19. The arc and arc gases having been expelled into the chute, cool insulating liquid from cavity 22 flows down over the end of contact 17 as soon as it passes below barrier 18. To facilitate this flow of liquid, openings, not shown, are left in the housing 5 enclosing the cavity. This covering of the contact 18 by insulating liquid prevents a re-establishment of the arc when the voltage is again restored. By the continued open circuiting movement of the switch the main and arcing contacts are carried to a full open position such as shown for example by Fig. 3. 130

Upon reclosing the switch the arcing contacts first connect with each other, the pawl 39 sliding over the ratchet 40 while the spring 35 is compressed. Finally when the parts 5 reach the fully closed position shown in Fig. 1, both arcing and main contacts are in engagement.

In addition to its effect in expelling the arcs into the chutes, the blow-out coils also 10 assist in the operation of the arms 38. The flux from each coil being in such a direction as to drive the arc outwardly exerts a thrust inwardly on the arm augmenting the electromagnetic effect of the loop of which the arm 15 forms a part.

In the modified form of my invention shown in Fig. 6, the movable contact is held in engagement with the fixed contact by the electromagnetic force of the current traversing the switch and is withdrawn therefrom only when this force reaches or approaches 20 a zero value. In this form of my invention the main contacts, the fixed arcing contact, the blow-out coil, arc chute, etc. are similar 25 to that shown in Fig. 1. The movable arcing contact, however, comprises the bridging member 50 secured at its central portion to the operating rod 25 and having the contacts 51 pivoted to the respective ends thereof. As illustrated, the ends of the bridging member are turned up at right angles and the adjacent portion of the contact extends 30 parallel to the bridging member or substantially so. A loop is thereby formed at each 35 end of the bridging member. While the switch is being moved to open circuit position the electromagnetic effect of these loops is to cause the cooperating contacts to remain in engagement with each other as long 40 as the instantaneous value of the current wave is not at or near zero. The electromagnetic force of the current on each contact is opposed by the spring 52 which connects the bridging member and contact mechanically 45 though preferably not electrically, the spring being suitably insulated at one end. Springs 53 between the same members serve to cushion the contacts and insure good connection when 50 the switch is in closed position irrespective 55 of the current passing there-through. During the opening movement of the switch the main contacts first separate shunting the entire load current through the arcing contacts as in the previously described form. The electromagnetic force of the current in 60 the loops hold the cooperating arcing contacts together until such time in the current wave is reached that the instantaneous value 65 is zero or near zero at which time springs 52 withdraw the movable contacts. Any small arc that may occur at this time is quickly 70 expelled into the arc chute and extinguished as already described. The movable contact also is covered by cool insulating liq-

uid as already described which prevents a re-establishment of the arc.

My switch has been used to break currents up to a dead short circuit at voltages ranging from approximately 15,000 volts to 96,000 70 volts. The latter voltage represents the highest available voltage within the limits of the testing apparatus then available and at this high voltage the switch showed no signs of distress. These results were obtained with a multiple break switch. The arrangement for extinguishing the arc is so effective that the average break for these tests was within approximately one half cycle of a twenty five cycle wave and with an approximate 75 break distance of only about two inches when the arc was interrupted, although the switch utilized on these tests did not embody the means on the movable contacts for ensuring final separation of the contacts at 80 or near the zero value of the current wave.

Although I have particularly described my invention in connection with a multiple break switch having a plurality of pairs of arcing contacts, it is apparent that a switch comprising merely a single pair of breaks is within the scope of my invention. Since the multiple break switch is in effect made up of a plurality of units, it is apparent that the illustrations in Figs. 1, 3 and 6, for example, 85 serve sufficiently to illustrate the single pair of breaks.

I prefer to arrange the arc chutes to expel the arcs and gases laterally in opposite directions and one advantage of this arrangement is that the reaction forces are balanced. A further advantage is that the hot gases are directed away from the main contacts and the operating rod.

While the various features of my invention 105 cooperate to produce a peculiarly efficient circuit breaking apparatus it will be apparent to those skilled in the art that certain features of my invention are advantageous whether or not others are used and that various changes and modifications may be made 110 without departing from my invention and I therefore aim in the appended claims to cover all changes and modifications within 115 the true spirit of my invention.

What I claim as new and desire to secure by Letters Patent of the United States, is:

1. Apparatus for interrupting an alternating current at or near the zero value thereof comprising cooperating fixed and movable contacts, conducting means forming a loop in circuit with the contacts including a movable portion arranged to control the separation of the contacts, and means for yieldingly opposing the electromagnetic effect of the current in said loop.

2. Apparatus for interrupting an alternating current at or near the zero value thereof comprising cooperating fixed and movable contacts, conducting means including a mov-

able member forming a loop in series with said contacts for controlling the separation thereof and a spring engaging the movable member arranged to oppose the electromagnetic effect thereon of the current in said loop.

3. Apparatus for interrupting an alternating current at or near the zero value thereof, comprising cooperating fixed and movable contacts, conducting means in circuit therewith including a movable portion arranged to control the separation of the contacts, and a blow-out coil for an arc drawn between said contacts arranged to affect said movable portion.

4. Apparatus for interrupting an alternating current at or near the zero value thereof comprising cooperating fixed and movable contacts, an operating member for the movable contact having a loose mechanical connection therewith and means responsive to a predetermined low instantaneous value of the current for making said connection fixed.

5. Apparatus for interrupting an alternating current at or near the zero value thereof comprising cooperating fixed and movable contacts, a member for moving the movable contact to open circuit position, means constructed to connect said member with said movable contact, and means responsive to the instantaneous values of the current for rendering said means inoperative while the current is greater than a predetermined low value.

6. Apparatus for interrupting an alternating current at or near the zero value thereof, comprising cooperating contacts, a member for moving one of said contacts from the other, a clutch connection between said member and said one contact, and means responsive to the instantaneous values of said current for controlling said clutch connection.

7. Apparatus for interrupting an alternating current at or near the zero value thereof comprising cooperating fixed and movable contacts, an operating member, a clutch connection between said member and said movable contact, and means controlling said connection forming a loop traversed by said current.

8. Apparatus for interrupting an alternating current at or near the zero value thereof comprising cooperating fixed and movable contacts, an operating member for the movable contact having a sliding mechanical connection therewith, means for yieldingly maintaining the movable contact in engagement with the fixed contact when the instantaneous value of the current is above a predetermined amount and for connecting together the movable contact and the operating member to cause a separation of the contacts when the instantaneous value of the current reduces to said predetermined amount.

9. An electric switch comprising a fixed contact, a cooperating movable contact, an operating member having a sliding connection with the movable contact, resilient means for maintaining the contacts in engagement with each other when the operating member is operated, clutch means for securing the movable contact to the operating member, and a clutch controlling arm forming a portion of a loop in the current circuit through the switch.

10. An electric switch comprising a pair of fixed contacts, a bridging member having contacts slidably mounted thereon for engaging the fixed contacts, ratchet mechanism for connecting the bridging member to the contacts carried thereby, ratchet controlling arms pivoted to the bridging member adjacent each slidable contact, and means connecting said arms in circuit with the slidable contacts whereby each arm forms a portion of a loop in the circuit.

11. An electric switch comprising a fixed contact immersed in insulating liquid, a structure associated therewith, forming a magnetic arc blow-out, and a blow-out chute therefor, a cooperating movable contact, and members in said chute connected respectively with said contacts to which member an arc drawn between the contacts is adapted to be transferred, said structure having a portion forming a reservoir from which insulating liquid flows to cover the movable contact after the arc has been transferred therefrom.

12. An electric switch comprising cooperating fixed and movable contacts immersed in insulating liquid, a structure associated with the fixed contact forming a magnetic blow-out and a blow-out chute therefor, said chute being closed on all but one side and having an opening on one side through which the movable contact is withdrawn, said blow-out coil being arranged to expel the arc in a direction substantially at right angles to the direction of movement of the movable contact.

13. An electric switch comprising a vessel containing insulating liquid, a contact housing supported in said liquid having a plurality of chambers open at one side thereof, a pair of relatively movable contacts arranged to separate in each of said chambers, means connecting said pairs of contacts in series, and means for expelling through the open sides of the chambers any arcs drawn between the contacts, said chambers having portions forming reservoirs from which insulating liquid flows to cover one of the contacts after the arc has been expelled therefrom.

14. An electric switch comprising a vessel containing insulating liquid, a contact housing supported in said liquid having a plurality of chambers open at one side thereof, a pair of fixed and movable contacts arranged

to separate in each of said chambers, means connecting the pairs of contacts in series, means for expelling through the open sides of the chambers any arcs drawn between the 5 contacts; each of said chambers being formed at that portion opposite the open side thereof with a pocket forming a reservoir from which insulating liquid flows to cover the movable contact after the arc has been 10 expelled therefrom.

15. An electric switch comprising a vessel containing insulating liquid, a contact housing supported in the liquid having a discharge opening at one side thereof, a fixed 15 arcing contact and blow-out coil therefor mounted in the chamber, a cooperating movable arcing contact, means connecting said blow-out coil and contacts in a series circuit, a fixed main current-carrying contact 20 secured to the exterior of the housing, a movable main current-carrying contact, and an operating rod for the movable main and arcing contacts, the opening of said chamber being arranged to direct a discharge away from 25 the operating rod and the main contacts.

16. An electric switch comprising a vessel containing insulating liquid, a pair of contact housings supported in the liquid, each of said housings comprising a plurality of 30 similar chambers having discharge openings at the same side of the housing, a blow-out coil and a fixed arcing contact in each chamber, an operating rod, movable arcing contacts carried thereby, and cooperating main 35 current-carrying contacts, said operating rod and main current-carrying contacts being arranged between said housings and the discharge openings of said chambers being arranged to direct the discharge therefrom in 40 opposite directions and away from the operating rod and main contacts.

In witness whereof, I have hereunto set
my hand this 21st day of December, 1928.

WILLIAM E. PAUL.
